Primary Examiner — Elizabeth J Oswecki(74) *Attorney, Agent, or Firm* — Dunlap Bennett & Ludwig PLLC(57) **CLAIM**

The ornamental design for an ornamental Christmas tree, as shown and described.

DESCRIPTION

FIG. 1 is a front perspective view of an ornamental Christmas tree, showing my new design;

FIG. 2 is a front elevation view thereof; the rear elevation view being a mirror image thereof;

FIG. 3 is a right elevation view thereof, the left elevation view being a mirror image thereof;

FIG. 4 is a top plan view thereof; and,

FIG. 5 is a bottom plan view thereof.

The broken lines shown in the drawings depict portions of the ornamental Christmas tree that form no part of the claimed design.
